CLAIM

The ornamental design for a knife holder for tufting machines, substantially as shown and described.

DESCRIPTION

FIG. 1 is a front perspective view of a knife holder for tufting machines embodying our new design, and illustrating one knife in phantom for illustrative purposes only;

FIG. 2 is a front elevational view thereof;
FIG. 3 is a side elevational view thereof as viewed from the left side of FIG. 2, the right side thereof being illustrated in FIG. 1 and is a mirror image of that illustrated in FIG. 3;

FIG. 4 is a rear elevational view thereof;

FIG. 5 is a top plan view thereof; and

FIG. 6 is a bottom plan view thereof.

FIG. 1

FIG. 2

FIG. 4

FIG. 3

FIG. 5

FIG. 6
